UNITED STATES PATENT OFFICE.

FRANK HURBERT ARMSTRONG, OF AUBURN, NEW YORK, ASSIGNOR TO CORONA TYPE-WRITER COMPANY, INC., OF GROTON, NEW YORK, A CORPORATION OF NEW YORK.

TYPEWRITING MACHINE.

Application filed January 29, 1919, Serial No. 273,789. Renewed September 21, 1920. Serial No. 411,814.

To all whom it may concern:

Be it known that I, FRANK H. ARMSTRONG, a citizen of the United States of America, and a resident of Auburn, county of Cayuga, State of New York, have invented certain new and useful Improvements in Typewriting Machines, of which the following is a full and clear specification.

This invention has relation to the line spacing mechanism and its object is to provide a simple and efficient device for clutching or clamping the usual line-spacing ratchet-wheel to the platen in such manner that a very secure connection is made between the two, so as to thereby provide the greatest possible insurance against slippage during regular line-spacing, the construction being such that the ratchet-wheel may be readily released from the platen to permit irregular or fractional line-spacing from time to time. The special objects of the preferred construction illustrated in my drawing are to do away with all actuating springs by causing the actuating devices to be frictionally held in either of their adjusted positions, and also to do away with the complication and insecurity involved in the use of jaws which have a biting engagement with the ratchet-wheel, as more fully herein-after set forth.

In the drawing—

Fig. 1 is a longitudinal sectional view taken through one end of a platen showing the parts in the position they assume during regular line-spacing;

Fig. 2 is a similar view showing the parts in position during fractional or irregular line-spacing;

Figs. 3 to 7 are detail views hereinafter described.

Referring to the drawing annexed by reference-characters, *a* designates the usual cylindrical platen, and *b* the usual platen-shaft affixed thereto in the usual manner at the end of the platen I have not shown in the drawing, and *c* a part of the frame of the platen-carriage. Affixed in a central recess in the end of the platen is a short metal tube *d* which projects beyond the end of the platen and whose inner end is turned inwardly to form an attaching flange *e* provided with holes *e* through which the fastening-screws *e* are passed.

Fitted and journaled within the outer end of the tube *d* is a rotatable head *h*, this head

being provided with an inwardly-extending hub *h* forming a cylindrical friction drum the periphery of which is adapted to be gripped by the locking levers *i*, and with an outwardly-extending hub *j* on which is rigidly affixed the usual line-spacing ratchet *k*, the extreme outer end of this hub *j* being reduced in diameter and journaled in the frame-member *c*.

The platen-shaft extends centrally through the head *h* and has slidably mounted on it a sleeve *l* which frictionally fits the bore of the head *h*. The outer end of the sleeve *l* projects beyond the frame-member *c* and has affixed to it a hand-wheel *m*, the end of the platen-shaft extending into the body of this hand-wheel and being provided with a head *n* at its extreme outer end which is adapted to prevent the hand-wheel and its attached sleeve from being slid off the platen-shaft when the hand-wheel is drawn outwardly to its extreme limit. The hand-wheel is affixed to the sleeve *l* by a set-screw *o* to permit the hand-wheel to be adjusted on the sleeve from time to time to compensate for wear and thus preserve a nice adjustment of the parts. In its innermost adjustment, the hub of the hand-wheel abuts against the outer end of hub *j* of the head to thereby afford a convenient abutment to stop.

The inner end of the sleeve *l* extends into an axial recess formed in the platen body and is exteriorly bevelled to form a wedge annular in cross-section. I prefer employing two of the gripping-levers *i*, arranged at diametrically opposite points. Each of these levers consists of an axially-extending slightly-springy arm *p* curved or inclined radially inwardly so as to be engaged by the bevelled surface of the sleeve when the sleeve is pushed inwardly. The forward end of this arm-member *p* extends into the tube *d* and is bent radially outwardly as well as toward the end of the platen to form an angular gripping-member *q*, the radial extension of this member being sufficient to permit the corners of this angular gripping-member to pivot at some point, preferably at *r*, on the interior wall of the shell-tube *d*, while the extremity is bent radially inwardly far enough to have a gripping engagement with the periphery of the hub *h*.

The rotatable head *h* is held in its proper position in the tube *d* by means of a shoul-

der *s* formed on the hub *j* and adapted to abut against the frame-member *c* and by an additional shoulder *t* which abuts against the end of the tube *d*; but for convenience in 5 assembling and for holding the rotatable head in the tube *d* during handling of the platen while off the machine, I provide an additional holding-device, namely, one or more screws *u* tapped radially inwardly 10 through the tube and entering an annular groove in the head.

It will be observed that when the hand-wheel and the attached wedge sleeve or tube are pushed inwardly to their limit, the 15 wedge-shaped inner end of the sleeve will radially spread the arms *p*. This will cause the levers to rock on the points *r* and thus swing the engaging ends of the levers into contact with the peripheral face of the 20 grip-hub *h'*, thereby firmly locking the rotatable head *h* together with its ratchet-wheel to the platen structure. Upon pulling the hand-wheel and the sleeve outwardly, the inner arms *p* of the levers will be 25 free to swing radially inwardly far enough to release the grip-hub *h'* and thus permit the platen structure to be rotated for irregular or fractional spacing independently of the ratchet-wheel and its attached head, 30 the ratchet-wheel being held against rotation by the usual detent device. It will be understood that the hand-wheel and its sleeve will be held in its outer adjustment or its inner adjustment by the friction of 35 the parts, an actuating spring being thereby rendered unnecessary. The pressure of the spring-arms *p* against the tube, when the tube is pushed in, serves to assist in holding the tube and its wheel *m* against creeping 40 outwardly by the jarring of the machine.

It will be observed that the relatively-rotatable head *h* formed with the two hubs *h'* and *j* has a broad bearing on the platen-shaft and that this head also is journaled 45 in the frame of the carriage while the end of the platen, through the medium of the fixed tube *d*, has a bearing on the head *h*. The result of this construction is that the 50 platen will at all times be maintained in a true central position and also will be substantially supported at the line-spacing end.

It will be observed that my device is 55 exceptionally compact and simple in construction. I not only do away with a spring for normally holding the actuating tube in either its out position or its in position, but I also provide an exceedingly simple 60 arrangement for gripping the ratchet-wheel-carrier, this arrangement consisting of a pair of simple levers loosely dropped into place during the assembling of the parts, pivot-pins for these levers being unnecessary and the levers being held in place 65

at all times by the mere placing of the rotatable head in the tube *d*. It will be observed that the levers are so shaped as to lie within the narrow annular space (substantially L-shaped in cross-section) 70 formed between the rotatable head and the flanged tube *d*. This arrangement not only conduces to compactness and strength, but also brings the periphery of the grip-hub *h'* into position where it may be firmly 75 gripped by the lock-levers. It will be observed that the gripping action takes place between the periphery of the grip-hub *h'* and the adjacent inner wall of the tube *d*, the outward thrust being taken up entirely 80 by the tube *d*, and the thrust radially-inwardly being taken up entirely by the metal mass of the hub *h'*, thereby relieving the platen-shaft entirely of thrust action and thereby avoiding all tendency to unduly 85 wear the shaft or its parts or to throw the shaft and the platen out of true.

A feature of importance lies in making the tail-end *p* of the levers springy, as thereby I not only avoid the use of means for 90 equally distributing the pressure between the two locking-levers, but I also provide for taking up any wear that may occur by engagement of the levers with the sliding tube. To ensure the levers rotating 95 with the platen at all times, they are arranged to engage in notches *v* formed in the annular flange *e*, and the movement of the levers longitudinally of the platen is prevented by said flange *e* and the inner face of 100 the grip-hub *h'*, so that although the lock-levers are not positively held by pivot-pins, they nevertheless always remain in operative position. With this type of locking mechanism, it will be observed that the locking-levers may be made very inexpensively, 105 since they may be readily stamped up from sheet-metal and tempered to give them the slight elasticity or springiness they require. To ensure the most powerful gripping engagement with the hub *h'*, the gripping-ends of the levers are pronged, as shown, so that the points of each prong will engage 110 the periphery of the hub at points separated circumferentially. Thus gripping 115 the grip-hub *h'* with a radially-inward thrust and at virtually diametrically opposite points ensures a sufficiently powerful gripping action to render it virtually impossible to rotate the ratchet-wheel and its 120 carrier independently of the platen while the gripping-levers are in locking position. To ensure the sliding sleeve *l* rotating at all times with the platen, this tube is flattened at one side, at *w*, and this flat face engages a straight edge *x* of the hole formed 125 in the circular flange *e*, as shown.

It will be observed that in the specific embodiment of my invention disclosed herein, the hub *h'* is smaller in diameter than the 130

interior of the platen-end-tube *d* and also that it terminates short of the fastening flange *e* thereof, thereby forming an annular space L-shaped in cross-section which communicates through the notches *v* with the axial recess in the platen body. In these annular spaces loosely lie the locking-levers, which levers are approximately Z-shaped in order to fulcrum on the interior of the end-tube *d* and properly grip the grip-hub *h*. In Fig. 7, I have shown more particularly the manner in which I prefer beveling the inner end of the tube *l*. In this view, the bevel is divided into a forward surface *l*'' and the rear surface *l*', the former being more obtuse than the latter and serving to quickly spread the lever-arms *p* when the tube is shoved in, while the other beveled part *l*' is relatively acute and serves to receive the pressure of the levers when the tube is shoved home. This longer and more acute beveled surface *l*' not only prevents the inward pressure of the spring-arms *p* from tending to force the tube axially outward, but also ensures a sufficiently long surface to provide for adjustment of the tube inwardly from time to time as the beveled parts wear.

The nature and scope of the invention having been thus indicated and its preferred embodiment having been specifically described, what is claimed as new is:

1. In a typewriting machine, a platen, a rotatable head fitted and journaled in the end thereof and carrying a ratchet-wheel at its outer side and a grip-hub on its inner face, within the platen, a slideable spreading member extending through the head and into the platen, and a rocking lever extending longitudinally of the platen and operated by said member and adapted to grip the outwardly-facing periphery of said hub, for the purpose set forth.

2. In a typewriting machine, a platen, a carrier for the line-spacing ratchet-wheel mounted in the end of said platen and carrying a grip-hub, a pair of rockable grip-levers whose grip-ends engage the periphery of said hub and whose operating or tail ends extend axially into the platen and are inherently springy, and a slideable wedge device for springing apart said tail ends of the levers to thus cause their gripping-ends to grip said hub.

3. In a typewriting machine, a platen, a line-spacing ratchet-wheel and a carrier thereof, this carrier being provided with a grip-ring, and means for locking the grip-ring and carrier to the platen embodying a lever having a gripping extremity engaging the periphery of said grip-ring, an inherently springy arm extending axially into the platen, and a slideable wedge-tube for operating said lever.

4. In a typewriting machine, a platen, a

line-spacing wheel and a carrier therefor provided with a grip-hub extending axially into the platen, a tube connected to the platen and surrounding said carrier and said grip-hub, a pair of rocking levers each embodying an elastic arm extending axially into the platen and a radial arm having a gripping-end extending radially inwardly and adapted to grip said grip-hub, and a slideable wedge-tube for spreading apart the elastic arms of said levers, for the purpose set forth.

5. In a typewriting machine, a platen having a metal tube in its end, a rotatable head fitted in this tube and carrying a ratchet-wheel at its outer end and a grip-hub at its inner end, and a locking device embodying gripping-fingers pivoting against the inner face of said tube and exerting a gripping frictional action against the periphery of said hub.

6. In a typewriting machine, a rotary platen, a line-spacing ratchet-wheel-carrier rotatably connected thereto, a slideable frictionally-held sleeve working through the carrier, and gripping means operated by said sleeve, said gripping means embodying resilient lever-arms extending into the platen.

7. In a typewriting machine, a rotary platen, a line-spacing ratchet-wheel carrier rotatably connected thereto, a slideable sleeve working through the carrier and having its inner end annularly beveled, this beveled part being divided into two surfaces, the one nearest the end of the tube being more acute in its angle than the other and the latter being longer than the former, and springy grip-levers actuated by said beveled surfaces, for the purpose set forth.

8. In a typewriting machine, a rotary platen, a line-spacing ratchet-wheel carrier rotatably connected thereto, the platen carrying a metal end-tube and the carrier being provided with a grip-hub of less diameter than said tube and extending thereto, thereby providing an annular space between said grip-hub and said tube, grip-levers extending into said annular space and provided with gripping-prongs adapted to engage the surface of said grip-hub, and means for actuating said grip-levers.

9. In a typewriting machine, the combination of a rotatable platen, a head adjacent one end of the platen rotatable relatively to the platen, a line-space wheel fixed on said head, said head being formed with a cylindrical gripping portion at its inner end, a rockable lever extending longitudinally of the platen and rotatable therewith, and a manually operable member extending through said head and slideable relatively thereto longitudinally of the platen having a cam surface for engaging one end of said lever and rocking the other end of the lever into en-

gagement with the gripping portion of said head.

10. In a typewriting machine, the combination of a platen shaft, a platen rotatable in unison with the shaft, a hub rotatable relatively to the shaft adjacent one end of the platen, a line-space wheel rotatable in unison with the hub, a pair of sheet metal levers having angular portions at their outer ends and resilient portions extending longitudinally within the platen, a sleeve slidable longitudinally on the platen shaft through said hub and having a beveled inner end for spreading the inner ends of the resilient portions of the levers apart and thereby rocking the outer ends of the angular portions of the levers into engagement with the perimeter of the hub under tension, a finger wheel adjustably held to the outer end of said sleeve, and means for limiting the extent of movement of the finger wheel.

11. In a typewriting machine, the combination of a platen shaft, a platen rotatable with the shaft, a line-space wheel, a carrier for the line-space wheel rotatable relative to the platen and provided with a friction surface concentric with the shaft, a lever rotatable with the platen having an arm provided with a gripping jaw at its outer end adapted to engage said friction surface and a resilient arm extending axially into the platen, and a manually shiftable sleeve slidably mounted on the platen shaft and extending through said carrier into the platen, said sleeve having a beveled inner end adapted to force the inner end of the resilient arm of the lever outwardly.

12. In a typewriting machine, the combination of a rotary platen, a cup-like metal member rotatable with the platen and set into one end of the platen with its open end facing outwardly, the inner end wall of said member having a central aperture and a pair of slots extending radially from the edge of said aperture, a line-space wheel carrier rotatable relatively to the platen formed with a cylindrical gripping portion at its inner end housed within the cuplike member, a line-space wheel fixed on the carrier, a pair of levers extending through the slots in the inner end wall of said member and having the outer portions thereof within said member extending radially and then outwardly over the perimeter of the gripping portion of the carrier, a sleeve extending slidably through the carrier and the central aperture in the cup-like member and having a cam portion for spreading the inner ends of the levers apart, and a finger wheel on the outer end of said sleeve.

13. In a typewriting machine, the combination of a rotary platen, a cup-like metal member rotatable with the platen and set into one end of the platen with its open end

facing outwardly, the inner end wall of said member having a central aperture and a pair of slots extending radially from the edge of said aperture, a line-space wheel carrier rotatable relatively to the platen formed with a cylindrical gripping portion at its inner end housed within the cup-like member, a line-space wheel fixed on the carrier, a pair of levers extending through the slots in the inner end wall of said member and having the outer portions thereof within said member extending radially and then outwardly over the perimeter of the gripping portion of the carrier, a sleeve extending slidably through the carrier and the central aperture in the cup-like member and having a cam portion for spreading the inner ends of the levers apart, and a finger wheel on the outer end of said sleeve, each of said levers having a rocking engagement with the inner surface of the cylindrical wall of the cup-like member adjacent the point of junction of the radially extending portion thereof with the portion overhanging the gripping portion of the carrier when the inner ends of the levers are spread apart.

14. In a typewriting machine, the combination of a platen, a cylindrical metal housing fixed in one end of the platen having an open outer end, a line-space wheel carrier having an enlarged intermediate portion journaled in the outer end of said housing and formed with a circumferential channel in its periphery, a plurality of screws threaded radially through the housing projecting into said channel, a line-space wheel fixed on the outer end of the carrier, a pair of levers extending longitudinally of the platen having angular outer portions within the housing rockable on the inner surface of the housing the outer ends of which are adapted to grip the inner end of the carrier, and means extending through the carrier into the platen and slidable longitudinally of the platen for spreading the inner ends of the levers apart.

15. In a typewriting machine, the combination of a rotatable platen, a hub at one end of the platen rotatable relatively thereto, a line-space wheel held to the hub, a pair of levers extending longitudinally of the platen and overhanging the perimeter of the hub at their outer ends, and means slidable longitudinally of the platen for forcing the outer ends of the levers against the perimeter of the hub under spring tension.

16. In a fractional line-spacing mechanism, the combination of a rotatable platen, a coaxial line-space wheel rotatable relatively to the platen, a clutch member rotatable with the line-space wheel having a circular peripheral friction surface, a resilient lever extending longitudinally of the platen and rotatable therewith, and manually shiftable

means engaging one end of the lever for rocking the opposite end of said lever toward the axis of the clutch member and forcing the same into engagement with the periphery of the clutch member under tension.

17. In a fractional line-spacing mechanism, the combination of a rotatable platen, a coaxial line-spacing wheel rotatable relatively to the platen, a clutch member rotatable with the line spacing wheel having a friction surface concentric with the axis thereof, a pair of diametrically opposed resilient levers extending longitudinally of the platen and rotatable therewith, each of said levers having laterally spaced jaws at one end, and manually shiftable means engaging the other ends of the levers for rocking said levers about axes extending transversely of the platen to force the jaws

into engagement with the friction surface 20 of the clutch member under tension.

18. In a fractional line-spacing mechanism, the combination with a rotatable platen and a line-spacing wheel, of a clutch member rotatable with one of said parts 25 having a peripheral friction surface, resilient gripping means rotatable with the other one of said parts and arranged to exert pressure on the periphery of the clutch member inwardly toward the axis of said member at 30 circumferentially spaced points, and manually operable means for forcing said gripping means into engagement with the periphery of the clutch member under tension.

This specification signed this 20th day 35 of December, A. D. 1918.

FRANK HURBERT ARMSTRONG.
